UNITED STATES PATENT OFFICE

2,261,183

AUTOMATIC TRAIN PIPE CONNECTOR

Joseph Robinson, New York, N. Y., assignor of
one-half to Roy M. Wolvin

Application December 15, 1938, Serial No. 245,841

7 Claims. (Cl. 285—24)

This invention relates to automatic train pipe connectors and is an improvement on the construction forming the basis of my United States Letters Patent #2,141,196, granted December 27, 1938, and my co-pending application Serial #244,932, filed December 10, 1938. Among the objects is to provide an improved fully automatic lock for positively locking mating connector heads together distinguished by the provision of means for effectively minimizing the leverage against the lock of the pressures carried in the heads. Heretofore, as typified in the aforesaid applications, it has been structurally necessary to apply the lock to the connector head at a point considerably above the center of the steam port where the greatest separating forces are carried. The result has been an over-strain on the lock and a pronounced tendency in the lock to creep open. To overcome this the lock and its seat were undercut, as shown at 37—38, Figure 4, in my United States Letters Patent #2,141,196, granted December 27, 1938, but then these parts stick and drag as they disengage while pressure remains in the connector heads. This fault was overcome, and desired powerful longitudinal draw on the heads towards each other was secured, by flaring the face of the lock and its seat outwardly as shown at 23—24, Figure 3, of my aforesaid co-pending application, Serial #244,932, filed December 10, 1938. However, this outward flare increased the difficulty of keeping the locks seated when under pressure. To meet this problem the lock-to-the-lock or anti-creep device shown herein and in my above co-pending application Serial #24,932, filed December 10, 1938, was developed. But the separating pressure in the steam port over the holding effect of the lock and the buffer spring still remained sharply multiplied, throwing excessive strains on the lock and its associated parts. One of the purposes of the present invention is to eliminate this fault, and lessen the tendency of mated heads to shift on each other and on their seats 36^a on the lugs 36 under the sharp whipping movement of speeding trains. This reduction in shifting tendency is accomplished by interlocking the ball and funnel members through the middle of the seats 16^a and 37^a. The special metallic bellows and gasket shown in Figures 4 and 5 for augmenting the tightness of the joint formed by my improvement, are divided from my aforesaid United States Letters Patent #2,141,196, granted December 27, 1938, and to that extent this application is a division thereof.

In the drawings, in which like reference characters indicate similar parts,

Figure 1 is a front elevation of my improved connector;

5 Figure 2 is a side view of Figure 1 with a part of the bracket C broken away;

Figure 3 is a plan view of the ball member showing certain parts of my improved lock;

10 Figure 4 is a horizontal section through the ball member 16 and through a part of the steam port showing my improved lock in the locked position. In this view a part of an adjacent connector head is shown, and

Figure 5 is an enlarged vertical section through 15 the steam port and its gasket looking toward the ball member 16.

The coupling head A is suitably mounted on a yoke B which spans and is yieldingly supported on the bracket C, for universal movement thereon, by the buffer spring D and tie rod E. The rod is hooked around the lug 10, Figure 2, of the bracket for pivotal movement thereon and it ties the spring D to the bracket under pressure through the medium of the adjustable stop 20 or seat F, the head A being yieldingly held at the limit of its forward movement by said spring with the flange 11 of the yoke pressed against the flat rear side 12 of the bracket. The bracket suitably attaches the connector to the usual lug 25 G of the car coupler not shown, with the front face of the uncoupled head A positioned in advance of the pulling face of the coupler two or three inches. The forward end of the yoke B is pressed into the shank 14 of the head or is otherwise secured to the head. The gathering 30 means of the head comprise a rearwardly extending shallow funnel 15 and a forwardly extending short stubby horn or ball member 16 having a removable part-spherical face 17, the 35 transverse center of the ball member and funnel being located in the horizontal plane occupied by the steam port hereinafter described. The ball member is hollow and is provided with spaced vertically arranged bearings 18—19. Bearing 19 lies in advance of the front or coupling face of the head A and bearings 18 lie behind such face. In the bearings 18 I mount a suitable pin 20, to which is rigidly secured, so as to rotate with the pin, a lock or dog J having an outwardly inclined face 21 adapted to mate with a similar face or seat 22, Figure 4, formed in the head A adjacent to the inner edge of the funnel and preferably on the horizontal center line of the funnel. The lock is actuated through a trigger 40 or throw member H pivoted on the pin 20 above

the ball member 16, and is provided on its rear side with a bearing or way 23 which merges into an overhanging forwardly extending laterally spaced release lug or finger 24, Figure 3. An anti-creep or lock-to-the-lock device K, which is also an actuating lever, is pivotally mounted on a pin 25 suitably arranged in the bearing 19 and is provided with a head 26 shaped to mate with and travel along the bearing or way 23. Normally the head 26 rests in the throat 27, Figures 3 and 4, formed by the outward spacing of the finger or lug 24 with respect to the body of the dog J, and preferably fits quite snugly therein. A U shaped spanner L straddles the finger 24 and the lever K and is pivotally connected to the latter by the pin 28. The base of the spanner threadingly receives, as at 29, Figure 3, the forward end of a plunger rod M which extends along the outside of the yoke B, through an opening at 30 in the flange 11, through the buffer spring D, and through a suitable bearing formed at 31 in the stop or seat F to slidably receive it. A timing nut or stop N is threaded to the rear end of the plunger M to adjust and time the throw of the lock J and to engage the rear side of the seat F to automatically draw the lock open, that is to say, away from the seat 24 on the head A, when mated connectors uncouple. A bracket P, Figure 2, is mounted on the rod M, inside the buffer spring D, and abuts a stop (not shown) on the road, the bracket being provided with an opening through which the tie rod E extends. A suitable actuating or lock spring Q, Figure 2, surrounds the tie rod with its rear end resting on a seat 32 formed on the plate F to receive it and with its forward end bearing against and resting on the plunger rod bracket P.

When a pair of connectors having my improved lock are coupled, the ports 33, 34 and 35, Figure 1, are brought into accurate alignment by the funnel 15 and ball member 16, the face 17 of the ball coming to final rest in the curved seats on the front face of a plurality or spaced bearing lugs 36. These lugs are formed integral with the funnel on its rear side and project into the large opening 37 of the funnel, Figures 1 and 4. Preferably they are so spaced that the lock seat 22 is between the two lugs that are nearest the vertical center of the head A. When the connectors are thus aligned, further coupling movement compresses the buffer springs D carrying the flange 11 away from the rear side of the bracket C. Inasmuch as the tie rod E is anchored to the bracket, and the plate F is anchored to the tie rod, the lock spring Q does not move rearwardly nor is it immediately compressed. Instead, the lock-to-the-lock or anti-creep device or lever K rocks forward on its pin 25, traveling along the way 23 of the trigger H, rotating the lock J through the opening 38 in the inner wall of the ball member 16, Figures 1, 4 and 5, into engagement with its seat 22. This brings the lock, the lever and the trigger to approximately the position shown in Figure 4. Further coupling movement of the connectors compresses the lock spring Q thus placing the lock J under a strong cam or wedging action through the medium of the lever K as the lever travels along the bearing or cam way 23 of the trigger H. Since the base rotates with the pin 20 by reason of the key 39, Figure 4, it is forced powerfully into the locked position, Figure 4, with adequate automatic take-up remaining in the lock to meet any condition of wear that may develop on the parts or on the joint between 75

mated coupling heads A. The cam or wedging action of the lock on the inclined lock seat 22 draws the coupling heads A longitudinally towards each other into firm interlocked position 5 with the gaskets in the ports 33, 34 and 35 compressed. The reverse of the coupling act just described opens the lock J and releases the head A. It will be apparent that the anti-creep device or lever K positively prevents the lock J from creeping open, and that it is not possible for any of the locking effect to be diminished by the pressure in the ports 33, 34 and 35. The construction produces what may be termed a lock to the lock arrangement which tends constantly to force the lock inwardly against the mating head and automatically compensate for or take up any wear that may occur on the locking parts or on the joint between mated heads.

An important feature of my improvement resides in the location of the horizontal center of the funnel 15 and ball member 16 with respect to the horizontal center of the buffer spring D. Heretofore the center of these several parts has occupied the same horizontal plane, as shown 25 in my United States Letters Patent #2,141,196, granted December 27, 1938. By moving the horizontal center of the funnel and ball member down to approximately the plane occupied by the horizontal center of the steam port 35, engagement of the lock J with its seat 22 is directly across the center of the steam port. As is well known, the greatest fluid pressure is in the steam port, and therefore the closer the lock is brought to the center of this port the less will be the strains on the lock and the better will be its holding effect. Sometimes the steam port pressure amounts to as much as 300 pounds or more per square inch. The result is excessive loads on the locking parts when they are located, 40 as heretofore, far above the center of the steam port. However rigid the holding effect of the lock there is always a tendency to shift the face 17 of the ball member 16 on its seat 36^a formed on the front face of the bearing lugs 36 when the cars whip around sharp curves, or over cross-overs at high speeds. To meet this condition effectively and lessen the strains it imposes on the lock, I provide the ball member 16 with an annular seat 16^a which drops into a complementary annular seat 37^a formed in the opening 37 of the funnel 15, Figures 1, 4 and 5. The walls of these seats are extended parallel to the longitudinal axis of the head A and the fit between them is quite close. They produce a firm 55 interlock against lateral and vertical shifting of mated heads relative to each other.

The efficiency and tightness of the joint formed by my improved lock, and novel location of the centers of the funnel 15 and ball 16, are materially aided by the new type of expansible bellows or pressure-actuated gasket U, Figure 5. This gasket, made of any material desirable for the purpose, includes a bellows 40 suitably anchored to the gasket head or face 41, as by brazing, spot-welding, shrinking or other method. At its rear the bellows is provided with a flaring flange 42 which is pressed tightly against a complementary annular seat 43 on the rear side of the steam port 35 of the coupling head A by the forward enlarged end 44 of the steam fitting 45. This fitting is adjustably supported on the flange 11 of the yoke B by means of a screw 46 and a supporting pin or other device 47. The arrangement is such that by releasing the screw the fitting 45 may be moved rearwardly out of its

seat in the head A and turned to one side with respect to the head sufficiently to permit easy removal and replacement of the gasket 40—41. When replaced in the port 35 the U-shaped guide or pilot 48 formed on the back of the head, and surrounding the upper half of the port 35, guides the fitting into its seat. By turning up on this screw 46 the fitting is pressed powerfully against the flange 42 of the bellows 40 forcing the same into liquid tight engagement with its seat on the head, and forcing the face 41 of the gasket tightly against an opposing gasket. Admission of steam to the gasket expands the bellows and automatically forces the parts into tightly sealed engagement.

What I claim is:

1. An automatic train pipe connector, comprising in combination, a coupling head provided with suitable guides and having a plurality of vertically spaced fluid-conducting ports, a support for said head, a lock for locking the head to a companion head, said lock being located in approximately the horizontal plane occupied by the center of the port in said head which carries the heaviest separating forces, and automatic means for operating said lock, said means including a plunger and a lock-to-the-lock device which engages the rear side of said lock and which is actuated by said plunger and positively prevents said lock creeping from the closed position toward the open position.

2. An automatic train pipe connector such as described in claim 1, in which the plunger and lock-to-the-lock device are pressure-actuated, distinguished further by the fact that said pressure is transmitted to said lock through said device and tends constantly to move the lock in against the companion head and automatically takes up any wear occurring on the locking parts or on the joint between the mated heads.

3. An automatic train pipe connector such as described in claim 1, in which the guides include a forwardly extending ball member and a rearwardly flaring funnel, distinguished further by the fact that the lock is mounted in the ball member and that the lock-to-the-lock device and said plunger are arranged on a vertical pivot outside said ball member and directly above said lock.

4. An automatic train pipe connector such as described in claim 1, distinguished further by the fact that means are provided for timing the movement of said lock-to-the-lock device with respect to the coupling and uncoupling movement of mating coupling heads whereby said lock is caused to move to the closed and open positions at a correct predetermined time in the course of said coupling and uncoupling movement.

5. An automatic train pipe connector such as described in claim 1, distinguished further by the fact that circumferential interlocking means are

provided on the periphery of the ball and in the apex of the funnel for cooperating with said lock to prevent mated heads shifting laterally or vertically on each other under the sharp whipping movement of speeding trains.

6. An automatic train pipe connector comprising, in combination, a coupling head, a bracket, a yoke connected with the head and extending to the rear of the bracket, said head being provided with a plurality of vertically spaced ports and having also ball and funnel guiding means, the ball being located on one side of the vertical center of the head and the funnel being located on the opposite side thereof, the horizontal center of said ball and funnel being in the same plane substantially below the center of said yoke and in approximately the horizontal plane occupied by the center of that one of said ports which carries the heaviest separating forces, a buffer spring 10 acting against said yoke to yieldingly hold the yoke normally against said bracket to project and yieldingly support said coupling head, a plunger extending from behind the head toward said buffer spring, a lock for the head adapted to be 15 moved into the locked position by said plunger when said spring is compressed in coupling, and means cooperating with the plunger to move said lock into and out of the coupled position and to 20 positively prevent the lock creeping from the closed position toward the open position, said lock being located in approximately the plane occupied by the horizontal center of said ball and funnel and being adapted to force mating heads longitudinally towards each other with a drawing 25 action as the locks close against said heads.

7. An automatic train pipe connector head, comprising in combination, a base disposed at a right angle to the longitudinal direction of the connector and provided with a part adapted to receive a support for the head, guiding means for said head attached to said base, said means including a forwardly extending stubby ball member and a rearwardly flaring shallow funnel, the funnel having a relatively wide opening through 30 its apex and provided with a plurality of spaced lugs which extend into said opening to receive the front face of the ball member on a mating head, said opening being provided with an interior seat adapted to receive a complementary exterior seat on said ball member to prevent mated heads shifting vertically or laterally on each other under the whipping movement of running trains, said exterior seat and the periphery of said ball being joined and both being disposed 35 well in advance of the front face of said base the horizontal center of said ball and funnel members being in a common plane substantially below the horizontal center of the part on said base of said head which receives said support and substantially above the bottom of said base.

JOSEPH ROBINSON.
